BOTTLE

Lawrence A. Bruns, Relay, Md., assignor to The
Crosse & Blackwell Company, Baltimore, Md.,
a corporation of Maryland

Application December 12, 1950, Serial No. 13,400

Term of patent 7 years

(Cl. D58—9)

To all whom it may concern:

Be it known that I, Lawrence A. Bruns, citizen of the United States, residing at Relay, in the city of Baltimore and State of Maryland, have invented a new, original, and ornamental Design for Bottle, of which the following is a specification, reference being had to the accompanying drawing, forming part thereof.

In the drawing:

Figure 1 is a front elevation of a bottle embodying my design;

Figure 2 is a side elevation;

Figure 3 is a rear elevation;

Figure 4 is a top plan view.

Both sides of the base are alike.

What I claim is:

The ornamental design for a bottle, as shown and described.

LAWRENCE A. BRUNS.
